UNITED STATES PATENT OFFICE

162,302

TUMBLER OR SIMILAR ARTICLE

Willard R. Horne, New York, N. Y., assignor to
Corning Glass Works, Corning, N. Y., a corpora-
tion of New York

Application June 20, 1950, Serial No. 10,641

Term of patent 7 years

(Cl. D36—8)

To all whom it may concern:

Be it known that I, Willard R. Horne, a citizen of the United States of America, residing at New York, in the county of New York and State of New York, have invented a new, original, and ornamental Design for a Tumbler or Similar Article, of which the following is a specification, reference being had to the accompanying drawing, forming a part thereof.

The sole figure is a side elevational view of a tumbler or similar article showing my new design. The decorative pattern is continued completely around the article.

The dominant feature of the design resides in the ornamentation on the tumbler as shown.

I claim:

The ornamental design for a tumbler or similar article, substantially as shown and described.

WILLARD R. HORNE.
